Perley K. Glass

UNITED STATES PATENT OFFICE.

PERLEY R. GLASS, OF BROOKLINE, MASSACHUSETTS, ASSIGNEE TO UNITED SHOE MACHINERY CORPORATION, OF PATERSON, NEW JERSEY, A CORPORATION OF NEW JERSEY.

SKIVING-MACHINE.

1,399,763.

Specification of Letters Patent. Patented Dec. 13, 1921.

Application filed February 13, 1919. Serial No. 276,850.

To all whom it may concern:

Be it known that I, PERLEY R. GLASS, a citizen of the United States, residing at Brookline, in the county of Norfolk and 5 State of Massachusetts, have invented certain Improvements in Skiving-Machines, of which the following description, in connection with the accompanying drawings, is a specification, like reference characters on 10 the drawings indicating like parts in the several figures.

This invention relates to leather working machines and is herein illustrated as embodied in a machine of the Amazeen type for 15 skiving the margin of a piece of upper leather.

In the manufacture of boots and shoes it is customary to skive certain portions of the margins of tips, vamps, quarters and other 20 parts of the upper. In some instances the margin is skived down to a thin edge preparatory to folding it; in others, the angle of the skive is slight, the purpose being merely to smooth the margin on the flesh 25 side. In the latter case, no folding is done, the raw edge being finished by applying stain to it.

The knife of a skiving machine is ordinarily rotated in such a direction with respect to the work being operated upon that the operative portion of the edge of the knife at any given instant is moving from the body of the work toward and over the edge thereof. In such case, the knife exerts a wiping 30 action outwardly with respect to the edge, and with certain kinds of work produces a more or less fuzzy or ragged edge due, for example, to projecting fibers of leather. If the skived margin is subsequently to be 35 folded a fuzzy edge of this kind is immaterial since it will not show in the finished work; but if a raw stained edge is to be produced, its appearance will be marred. In order to prevent the formation of a fuzzy 40 edge, where a raw, stained edge is the final result sought, it has been customary to reverse the knife by changing its driving mechanism in some manner, for example, by crossing the knife driving belt if it is ordinarily open. This reversal of direction of 45 rotation of the knife causes the loose ends of the fibers of the work to be wiped back over the body portion so that a clean cut edge is produced. Changing the path of the

knife driving belt, however, necessitates 55 stopping the machine and usually the provision of extra guide pulleys.

According to one feature of the present invention, means under control of the operator during the running of the machine are 60 provided for changing the manner in which the tool of a machine is driven while maintaining the actuation of the feeding means unchanged. In the illustrative machine the tool is a rotary disk knife and the feeding 65 means a rotary roll. The knife is driven directly by a belt from a driving shaft, the direction of rotation of which may be reversed at any time. The roll is driven indirectly from the driving shaft through 70 suitable mechanism constructed and arranged to maintain the direction of rotation of the roll unchanged irrespective of the direction of rotation of the driving shaft. With this construction the operator may at 75 any time reverse the direction of rotation of the driving shaft and thereby of the knife without changing the direction of rotation of the feed roll, so that whereas formerly it was necessary to stop the machine and make 80 a change in the driving mechanism in order to reverse the direction of rotation of the knife without changing the operation of the feed roll, it is possible to accomplish the same 85 result with the present machine by merely manipulating a belt shifter to change the direction of rotation of the driving shaft.

This and other features of the invention, including certain details of construction and combinations of parts, will be described as 90 embodied in an illustrative machine and pointed out in the appended claims.

Referring now to the accompanying drawings,—

Figure 1 is a front elevation, with certain parts in section, of a machine in which the present invention is embodied, and

Fig. 2 is a perspective showing the mounting of the feed roll.

The machine is of the Amazeen type and 100 comprises a rotary disk knife 3, a rotary feed roll 5, and a rotary feed disk 7, these parts being adapted to operate as usual in this type of machine. The knife is mounted in bearings in an overhanging arm which is 105 part of the frame 9 of the machine, the upper end of the knife shaft 11 extending into a bearing 13 and the lower end extend-

ing through the stationary sleeve 15 which is mounted in the end of the arm 9. The pulley 17 fast to the knife shaft is located between the upper end of the sleeve 15 and 5 a nut 19 which is threaded on the shaft 11. With this construction it will be noted that the knife shaft has no adjustment. The knife is driven by a belt 21 which passes around the pulley 17, over a small pulley 23 10 the axis of which is fixed, around a large pulley 25 which is fast to a driving shaft 27, and back over a small pulley 29 rotatably mounted in an arm 31 which is pivoted to the frame of the machine at 33. This arm 15 has rotatably mounted at its lower portion a roller 35 which is adapted to be engaged by a cam 37 formed on the end of a lever 39 which is pivoted to the machine at 41 and may be rocked about its pivot by exerting 20 a downward pull upon a treadle rod 43. A treadle, not shown, is connected to the rod, and a spring, also not shown, acts upon the treadle so as normally to raise the treadle rod and maintain the lever 39 in the position 25 shown. When, however, the treadle is depressed and the arm 39 rocks in a counter clockwise direction about its pivot, the cam 37 engages the roll 35 to swing the arm 31 about its pivot 33 and thereby raise the small 30 pulley 29 so as to tighten the belt 21. Fast to the shaft 27 is a pulley 45, and located one on each side of this pulley are two loose pulleys 47, 49. The fast pulley 45 may be 35 driven either by a crossed belt 51 or, as shown, by an open belt 53, these belts being driven from the usual counter shaft, not shown, located beneath the bench upon which the machine rests. A belt shifter 55 having a handle 57 is slidable on a square rod 40 59. With the position of the parts shown, the pulley 45, and consequently the shaft 27, is being rotated in a given direction by the 45 open belt 53. If now the belt shifter is moved to the right, the open belt 53 will be transferred to the loose pulley 49 and the crossed belt 51 will drive the pulley 45, and consequently the shaft 27, in the opposite direction. It will thus be clear that at any 50 time the two belts may be shifted to reverse the direction of rotation of the knife 3.

In order to insure that the direction of rotation of the feed roll shall remain the same irrespective of the direction of rotation of the knife, the following construction is 55 employed. A counter shaft 61 rotatably and slidably mounted in bearings in the frame of the machine has mounted upon it a gear 63 which meshes with a worm 65 formed upon the shaft of the small pulley 60 23. The gear 63 is connected with the shaft 61 by means of a screw 66 the lower end of which extends into a diagonal groove 67 in the shaft 61. This groove extends only part way around the shaft so that the lower end 65 of the screw 66 contacts with one end or

the other of the groove 67 according to the direction of rotation of the gear 63. Loose on the shaft 63 are two pulleys 69, 71. An open belt 73 passes around the pulley 69 and around one of the grooves of a double pulley 75 which is loose upon the short shaft 77. A crossed belt 79 passes around the pulley 71 and around another groove in the double pulley 75. The hub of the pulley 69 has mounted in its end a pin 81, and the pulley 75 71 has mounted in it a similar pin 83. Driven through the shaft 61 is a pin 85 which is adapted to coöperate alternately with the pins 81 and 83 and thereby to impart rotation either to the pulley 69 or to 80 the pulley 71. With the parts in the position shown, the shaft 61 is in its right-hand position and is rotating in the direction indicated by the arrow. The pin 85 is in contact with the pin 81; and consequently the pulley 69 is being rotated and through the belt 73 is rotating the pulley 75 in the same direction that the counter shaft 61 is rotating. If now, the belt shifter 55 is manipulated to reverse the direction of rotation of 85 the driving shaft 27, the direction of rotation of the gear 63 will be reversed. This will cause the end of the screw 66 to travel in the oblique slot 67 and move the shaft 61 to the left, thereby disengaging the pin 85 from the pin 81 and causing it to engage the pin 83. The power will now be applied from the shaft 61 to the pulley 71. In this case, the shaft 61 will be rotating in the direction opposite to that indicated by the 90 arrow; but because of the crossed belt 79, the direction of rotation of the pulley 75 will remain unchanged. As will presently appear, the direction of rotation of the pulley 75 determines the direction of rotation of 95 the feed roll 5.

The shaft 77 is connected by a universal joint 87 with one end of a floating shaft 89 the other end of which is connected by a similar universal joint 91 with a shaft 93 to 100 which the feed roll 5 is fastened. As shown in Fig. 1, the shaft 93 has a reduced portion at its end which extends through a bore in a partition in the interior of the roll and has threaded on its end nuts 95 so that the 105 roll is rigid with the shaft 93. The bearing 97 for the shaft 93 is pivoted at 99 to the outer end of an arm 101 and has on its under side a projection which fits in a groove formed in the arm 101 so as to insure that the tipping of the bearing 97 about the pivot 99 shall take place in a vertical direction without side play. In order to adjust the bearing and consequently the roll about the pivot 99 so as to vary the angle of the skive, 110 the bearing has an extension provided with a square slot 103 in which fits a block 105 loosely mounted on a small crank pin 107 which is carried by a disk 109. The disk is fast to one end of a shaft having a bearing 115

in the arm 101 and provided at its opposite end with a head 111 having a scale marked thereon, any one of the divisions of which may be brought into register with a mark 5 on the bearing. A handle 113 is provided for making this adjustment; and a spring washer 114 is provided to hold the parts in adjusted position. The arm 101 is pivoted at 115 between upstanding ears on a support 10 117 and is adjustable about said pivot by means of a thumb nut 119. This thumb nut is mounted between the arms of a yoke formed at the end of the support 117 and is threaded to receive a screw 121, said screw 15 being held from turning by a pin 123 which enters a slot in the screw, not shown. The arm 101 is guided in its movement about the pivot 115 by ears formed upon the support 117 one of which is shown at 125. The 20 pivot 115 is located at a sufficient distance from the roll 5 so that when the arm 101 is swung about the pivot, the movement of the roll is approximately vertical, the purpose of this adjustment being to provide 25 for different thicknesses of stock. In order to permit the roll to be adjusted toward and from the knife in the line of feed, the support 117 is pivotally fastened to the frame of the machine by a bolt 127; and the support 30 may be swung about the axis of this bolt by turning a thumb nut 129, said thumb nut being fast to a screw which is held from longitudinal movement with respect to the frame of the machine and threaded into 35 a depending lug on the support. A presser foot and gage, indicated as a whole by the numeral 131, is mounted on the arm 101. This presser foot and gage is, or may be, substantially the same as that shown in the 40 patent to Alexander No. 1,180,222 and will not be further described.

As has been explained, the double grooved pulley 75 is loose on the shaft 77. In order 45 to clutch it to the shaft when desired a cap 133 is slidably keyed on the shaft and is adapted to be moved by means of a lever 135 which, like the lever 39, is pivoted at 41 to the frame of the machine. This lever has a depending portion 137, rectangular in 50 cross section, which is adapted to be engaged by the lower face of the lever 39 when the treadle rod 43 is given a downward pull. It should be noted, however, that the first effect of a downward pull upon the treadle 55 rod 43 is to cause the cam 37 to engage the roll 35 and thereby, by tightening the belt 21, to apply power to the knife 3. Further downward movement of the lever 39 causes it to engage the depending portion 137 so 60 as to rock the lever 135 and thereby clutch the pulley 75 to the shaft 77 and apply power to the feed roll. It should be noted that by varying the force of the downward pull upon the rod 43, more or less of a slip 65 may be permitted between the end of the

pulley 75 and the adjacent end of the cap 133 so as to vary the rate of rotation of the feed roll. Such a construction is desirable particularly when a piece of work, a portion of the edge of which is sharply curved, is 70 being operated upon since, when the sharply curved edge is encountered, it is desirable to decrease the rate of feed.

The stem of the feed disk 7 is mounted in bearings in a bracket 139 which is carried 75 by the arm 101 so that the feed disk partakes of all the adjustments of said arm. A spring 141, the tension of which may be varied by turning a screw 143, engages the top of the spindle of the feed disk so as to 80 hold it yieldingly against the work. A grinder 145 of the usual type is provided, said grinder being driven in the usual manner by means of a belt 147.

In the use of the machine, power is 85 applied continually to the belts 51 and 53. With the parts in the positions shown, the belt 21 is loose and consequently power is being applied only to the driven shaft 27. Depression of the treadle first applies power 90 to the knife to rotate it and then applies power to the feed roll. If at any time the operator desires to reverse the direction of rotation of the knife, he has merely to manipulate the handle 57 of the belt shifter. 95 It is thus possible to reverse the direction of rotation of the knife at any time during the running of the machine without changing the direction of rotation of the feed roll.

Having thus described my invention, what 100 I claim as new and desire to secure by Letters Patent of the United States is:

1. A machine of the class described, having in combination, a tool, means for driving the tool in a given manner and at a 105 given speed, feed mechanism, means for operating said mechanism to advance the work to the tool, and means capable of being manipulated by the operator during the running of the machine for changing the 110 manner in which the tool is driven while maintaining the velocity of the tool and the operation of the feed mechanism unchanged.
2. A machine of the class described, having in combination, a tool, means for driving the tool in a given direction, feed mechanism, means for operating said mechanism to advance the work to the tool, and means capable of being manipulated during the 115 running of the machine for reversing the 120 direction in which the tool is driven while maintaining the operation of the feed mechanism unchanged.
3. A machine of the class described, having in combination, a knife, means for driving the knife in a given direction, feed mechanism, means for actuating said mechanism to advance the work to the knife, and means under the control of the operator during the running of the machine for revers- 125

65 70 75 80 85 90 95 100 105 110 115 120 125 130

ing the direction in which the knife is driven while maintaining the direction of feed of the work unchanged.

4. A machine of the class described, having in combination, a knife, a feed roll, a driving shaft, means for driving the shaft, means for driving the knife and the roll from the shaft, and means for reversing the direction of rotation of the shaft and thereby of the knife while maintaining the direction of rotation of the feed roll unchanged.

5. A machine of the class described, having in combination, a rotary knife, a rotary feed roll, and means whereby the direction of rotation of the knife may be reversed during the running of the machine while maintaining the direction of rotation of the feed roll unchanged.

6. A machine of the class described, having in combination, a knife, a feed roll, a driving shaft, a counter-shaft, means for driving the knife directly from the driving shaft, means for driving the roll through the counter-shaft, and means for reversing the direction of rotation of the driving shaft and thereby of the knife and counter-shaft while maintaining the direction of rotation of the roll unchanged.

7. A machine of the class described, having in combination, a tool, means for feeding work to the tool, a driving shaft, a counter-shaft, means for rotating the counter-shaft from the driving shaft, a feed shaft, two pulleys fast to the feed shaft, two pulleys loosely mounted on the counter-shaft and adapted to be connected with it alternately, means connecting one of the pulleys on the counter-shaft with one of the pulleys on the feed shaft constructed and arranged to compel the two pulleys to rotate in the same direction, means connecting the other pulley on the counter-shaft with the other pulley on the feed shaft constructed and arranged to compel the two pulleys to rotate in opposite directions, and means whereby reversing the direction of rotation of the driving shaft frees one of the counter-shaft pulleys from driving connection with the counter-shaft and connects the other one with it.

8. A machine of the class described, having in combination, a rotary disk knife, a feed roll, means whereby the roll may be adjusted toward and from the plane of the cut of the knife, means whereby the roll may be adjusted substantially parallel to said cut, and means whereby the inclination of the axis of the roll may be varied.

9. A machine of the class described, having in combination, a rotary disk knife, a

feed roll, means whereby the roll may be adjusted substantially vertically toward and from the knife, means whereby the roll may be adjusted substantially horizontally toward and from the knife, and means whereby the inclination of the axis of the roll may be varied.

10. A machine of the class described, having in combination, a knife, a roll for advancing the work to the knife, a shaft to which the roll is fast, a bearing for the roll shaft, an arm to which the bearing is pivoted, a support to which the arm is pivoted, and means whereby the support may be adjusted to adjust the feed roll toward and from the knife substantially in the line of feed of the work.

11. A machine of the class described, having in combination, a knife, a roll for advancing the work to the knife, a shaft to which the roll is fast, a bearing for the roll shaft, an arm to which the bearing is pivoted, means whereby the bearing may be adjusted with respect to the arm, a support to which the arm is pivoted, and means whereby the support may be adjusted to adjust the feed roll toward and from the knife substantially in the line of feed of the work.

12. A machine of the class described, having in combination, a knife, a roll for advancing the work to the knife, a shaft to which the roll is fast, a bearing for the roll shaft, an arm to which the bearing is pivoted, a support to which the arm is pivoted, means whereby the arm may be adjusted with respect to the support, and means whereby the support may be adjusted to adjust the feed roll toward and from the knife substantially in the line of feed of the work.

13. The combination with a driving shaft and a driven shaft, of a counter-shaft, means for rotating the counter-shaft from the driving shaft, means for rotating the driven shaft from the counter-shaft, and means for reversing the direction of rotation of the driving shaft and thereby of the counter-shaft while maintaining unchanged the direction of rotation of the driven shaft.

14. A machine of the class described, having in combination, a frame having an overhanging arm, a rotary knife shaft mounted in said arm and held from movement in any manner other than rotary, a disk knife fast to the lower end of the shaft, a feed roll located beneath the knife, and means whereby the feed roll may be adjusted both angularly and toward and from the knife.

In testimony whereof I have signed my name to this specification.

PERLEY R. GLASS.
